UNITED STATES PATENT OFFICE.

JOHN OAKLEY, OF SPRINGFIELD, MASSACHUSETTS.

BROACH.

1,359,831.

Specification of Letters Patent. Patented Nov. 23, 1920.

Application filed June 25, 1918. Serial No. 241,748.

To all whom it may concern:

Be it known that I, JOHN OAKLEY, a subject of the King of Great Britain, residing at Springfield, in the county of Hampden and State of Massachusetts, United States of America, have invented certain new and useful Improvements in Broaches, of which the following is a specification.

My invention relates to improvements in tools of the drift or broach type, which are used to cut grooves, channels, slots, and the like in various objects, and consists essentially of a shank provided with teeth having outer, transverse, cutting edges, and having 10 depressed surface, chip-clearance passages opening at the rear end, together with such other parts and members as may be needed or desired to render the tool complete and serviceable in all respects, all as hereinafter 15 set forth.

With this broach the original slot in the stock may be cut, or a slot previously cut may be widened, according to the manner in which my invention is applied in the tool 20 used.

The primary object of my invention is to produce a broach for cutting slots radially, in which there is ample clearance for the chips, so that clogging is prevented and 30 there is no liability of injuring, by chipping, slivering, or tearing, the stock, such clearance being exterior, in contradistinction to interior such as the longitudinal and lateral passages employed in the broach which 35 forms the subject of my Letters Patent of the United States, No. 1,272,841.

A further object is to provide means in a tool of this kind to facilitate the clearance of the chips by cutting or splitting the chips 40 as they are cut from the stock by said tool, to the end that the latter can be equipped with wider teeth, for cutting a wide slot initially, then would be possible without ample provision for taking care of the resulting 45 wide chips.

With a tool embodying my invention I am able to broach a wide slot with great accuracy and high finish, and in less time than is commonly required for the same work 50 performed with the old type of broaching tool.

Another object is to afford means for readily removing and replacing the teeth of a broach, and thereby increasing the life of 55 the broach as a whole and generally enhanc-

ing the utility and serviceability of the broach.

Still another object is to provide a broach which is strong and durable, comparatively inexpensive to construct, and withal highly 60 practicable and efficient.

Other objects and advantages will appear in the course of the following description.

I attain the objects and secure the advantages of my invention by the means illustrated in the accompanying drawings, in 65 which—

Figure 1 is a side elevation of a broach which embodies a practical form of my invention, the middle portion of said broach 70 being broken out in this and in Figs. 8, 9, and 10 to economize space; Fig. 2, a top plan of the front end portion of said broach; Fig. 3, a cross section through said broach, taken on lines 3—3, looking in the direction of the 75 associated arrow, in Fig. 1; Fig. 4, a cross section through the broach, on lines 4—4, looking in the same direction as before, Fig. 1; Fig. 5, an end elevation of a piece of stock, illustrating the operation or purpose 80 of said broach; Fig. 6, a top plan of a fragmentary portion of a broach which is equipped with means to split the chips as they are cut by the teeth of the broach; Fig. 7, a central, longitudinal, vertical section 85 through the aforesaid fragmentary portion; Fig. 8, a top plan of a broach which embodies another practical form of said invention; Fig. 9, a combined side elevation of and central, longitudinal, vertical section 90 through said last-named broach; Fig. 10, what may be termed a side elevation of a broach which illustrates still another embodiment of the invention; Fig. 11, a cross section through the Fig. 10 broach, on lines 95 11—11, looking in the direction of the associated arrow, in that view Fig. 12, a bottom plan or inside elevation of one of the teeth employed in the last broach; Fig. 13, an end elevation of a piece of stock, illustrating the 100 operation or purpose of the Fig. 10 broach; Fig. 14, what may be termed a top plan of the front end portion of a broach that embodies still other features of novelty, or a 105 different or modified adaptation of such features, and, Fig. 15, what may be termed a side elevation of the broach elements shown in the last preceding view.

Similar reference characters designate similar parts throughout the several views. 110

It should be noted in passing that the diameter of the shank of each broach is the same as that of the main passage through the stock, and the width of each wide tooth 5 is equal to that of the slot to be cut, whether original or widened, in said stock. The heights or radial depths of the teeth of any of these broaches increase from front to rear, as is the case with the teeth of ordinary broaches.

In some cases there is a plurality of rows of teeth on a shank. The row or rows of teeth may be arranged spirally on the shank. Usually the teeth will be attachable to and 15 detachable from rather than integral with the shank. In the event the broach is designed to widen a slot already cut, said broach is preferably provided with a pilot or equivalent means for guiding the teeth.

20 In matters of shape, size, arrangement, and construction of the parts of my invention, it is to be understood that other modifications, in addition to those illustrated in connection herewith, may be made without 25 departing from the nature of said invention or exceeding the scope of what is claimed, wherefore I do not desire or intend to be restricted to the several embodiments shown and described in detail.

30 Referring to the drawings, I will first describe the broach illustrated in the first five views, which is a widening tool, but may be used for the original or initial cutting of a wide slot, as will presently be more clearly 35 explained; then I will describe the splitting device for the chips, shown in Figs. 6 and 7; next I will take up the broach shown in Figs. 8 and 9, which is equipped with narrow and wide teeth for cutting a wide slot 40 in the stock in the first instance, and this without undue strain on the tool or injurious action on the stock; following I will explain the Fig. 10 broach which has three rows of teeth, and, finally, I will explain the broach 45 having two rows of spirally arranged teeth of Figs. 14 and 15. But before proceeding with the several detailed descriptions and explanations, I desire to call attention to the fact that each broach comprises a shank 1, 50 which is provided at the forward or leading terminal with suitable means for attaching said broach to the machine, as a screw-threaded puller-head 2, the same being partly broken off in several of the views, and 55 a plurality of teeth having outer, transverse, cutting edges, which differ more or less in different broaches.

The teeth of the broach which forms the subject of this application are teeth which 60 cut with their outer transverse or substantially transverse, or circumferential edges, in contradistinction to teeth that cut with their lateral radial edges. The teeth in the present case cut into the stock radially, that is, from the inner periphery toward the

outer periphery, while the teeth in the other case cut into the stock on the sides of a previously formed slot. Broaches having the latter type of teeth form the subject of Letters Patent of the United States, No. 70 1,293,887.

Mounted on the shank 1 of the first broach, which is the broach of Figs. 1, 2, 3, and 4, is a row of flat, rectangular teeth 5, each secured to said shank by two screws 6. The front edge of each tooth 5 is undercut or beveled from the outside inward and rearward to form the front, outer edge of said tooth a cutting edge 7. Two longitudinal chip-clearance passages or channels 8 are formed in the shank 1, one on each side of that part of said shank to which the teeth 5 are directly secured by the screws 6. The channels 8 are cut into the side of the shank and extend from points in advance of the transverse plan of said shank in which is located the foremost cutting edge 7 to the rear end of said shank, through which end said channels open. The teeth 5 overhang the channel 8 on both sides. Said teeth, as 90 shown, are all of the same thickness and let into the shank 1 in such a manner as to obtain the stepped arrangement required in broaching, the foremost tooth being set in the most, the next being set in not quite so 95 far, the third less, and so on, the rearmost tooth being set in the least of all. A pilot 9, of the same width and depth as the width and depth of slot which this tool is designed to widen, is located on the shank 1 in advance of the row of teeth 5 and in the central, longitudinal plane of said row. The pilot 9 is formed on the outer end of a plug 10 which fits within a recess in the shank, and is secured therein by a transverse pin 12 100 passing through said shank and plug. The central portions of the cutting edges 7, which are in direct line with the pilot 9, do no cutting, but the outlying portions of said edges cut away the stock to widen the original slot. It is plainly to be seen, then, that the chips cut by the teeth 5 must pass directly into the channels 8 and through the latter to escape at the rear end of the shank. That part of the shank 1 which directly supports the teeth 5 is no wider than the pilot 9, consequently there is nothing to divert the chips from their downward courses against the beveled front edges of said teeth, as soon as said chips are cut, and into the 110 channels 8. The outer faces of the teeth 5 are beveled slightly for clearance as usual, and the same thing is true of the teeth in the other examples of broaches shown in connection herewith.

Assuming now that a piece of stock 13, Fig. 5, have a central opening or passage 14 and a slot 15 therethrough, which slot it is desired to widen, and that the shank 1 of the broach just described will fit said passage 130

and the pilot 9 of said broach will fit said slot, while the width of the teeth 5 of said broach corresponds with the width of the required slot, and the depth of the rearmost tooth is equal to the depth of the slot, the operation of widening is as follows: The forward end of the shank 1 is introduced into the passage 14 and the pilot 9 into the slot 15, and the tool is drawn forcibly through said passage and slot, with the result that the cutting edges 7 or the portions thereof that overhang the channels 8 progressively cut away the inner periphery of the stock both sides of said slot, as indicated by broken lines 16 in Fig. 5, forming first the inner corners of the enlarged or widened slot and working radially or outwardly until finally the wide slot complete is produced. Owing to the fact that the first few cuts in the widening operation are on chords of the opening 14, the teeth 5 which make said cuts must be depressed so much that their cutting edges 7 are below the periphery of the shank 1.

25 The pilot 9 leads and the teeth 5 follow and cut the slot the full width and deeper and deeper the farther the tool progresses, as is clearly apparent. The chips cut by the teeth 5 on both sides of the slot are directed by the 30 beveled front edges of said teeth into the passages or channels 8, and said chips pass freely through said channels and finally off at the back end of the tool.

This widening tool can be converted into a primary-slot broach by forming channels down each side, from the central, longitudinal plane of the row of teeth 5, to the main channels 8, two of such branch channels appearing at 17 in Fig. 6, by omitting the pilot 40 9, and preferably by locating a cleaver, as 18 in Figs. 6 and 7, in front of each of said teeth. The cleaver 18 is simply a post, which has a knife-edge top, set into the shank 1, with said knife-edge top in the aforesaid central, longitudinal plane and a little below or inside of the cutting edge 7 of the adjacent tooth 5, the back of said cleaver being beveled off at the top to enable it to fit tightly the beveled front edge of said tooth. A pin 50 19, which passes transversely through the shank 1 and the post of the cleaver 18, may be used to secure said cleaver in place.

In practice the second broach is used in practically the same way as the first, but in 55 this case each tooth 5 cuts a chip the full width of the tooth or of the cutting edge 7 of said tooth, the chip immediately encounters the cleaver 18 and is thereby split lengthwise as the tool advances, and the two lengths 60 of chip thus formed pass down the branch channels 17 into the main channels 8, and on out of the way. Thus there is no danger that the broach will become clogged with the chips, even though chips of unusual width 65 are cut as is the case with the second broach.

Passing next to the third broach, that shown in Figs. 8 and 9, it will be seen that this broach has alternately arranged narrow teeth 20 and wide teeth 5. By providing the broach with the narrow and wide teeth, I 70 am able to cut a wide slot with the single tool expeditiously, accurately, and with comparative ease. This broach is really a combination of the broach of my United States Patent No. 1,272,841, and the broach herein first 75 described. The teeth 20 are received in transverse passages 21 in the shank 1, they are secured with transverse pins 22, and said passages open at one end through the top or one side of said shank, and at the other end 80 into a longitudinal passage 23 in said shank, all as fully set forth in said Patent No. 1,272,841; while the teeth 5 are mounted on the shank and secured with the screws 6, as in the first instance. The teeth 20 have cutting edges 24 at the outer end of their front edges. One of the teeth 20 leads, then follow in a row the teeth 5 and 20 arranged alternately, until the rear end of the shank is reached where there are two teeth 5 instead 85 of one only. The cutting edge 7 of each tooth 5, with the exception of the cutting edge of the rearmost tooth 5, projects less than the cutting edge 24 of the tooth 20 immediately in front, for the reason that, during the first part of the cutting operation the chord in the bore of the stock which corresponds with or represents the width of the cut of the wide tooth is longer than the chord in said bore which corresponds with 90 or represents the width of the cut of the narrow tooth. If the first narrow and the first wide cutting edges were on the same plane parallel with the longitudinal center 95 of the shank, the second narrow and the second wide cutting edges on the same plane parallel with said center, and so on, the wide cutting edges might be required to make cuts which would be too deep to be practicable. The difference in depth of cut between each narrow tooth and the wide tooth immediately behind is compensated for by the addition of the extra, wide tooth at the rear end, which tooth has a cutting edge that is level with the cutting edge of the rear- 100 most narrow tooth.

When the third broach is in use the foremost tooth 20 first makes a narrow cut in the stock, then the foremost tooth 5 makes a wide cut which is nearer the axial center 120 of the shank than is the initial cut, next the second tooth 20 cuts a little deeper the width of its cutting edge, likewise the second tooth 5, and so on until finally the last tooth 5 removes the stock remaining in the slot after 125 the last tooth 20 and the next to the last tooth 5 have made their cuts, and leaves the innermost wall of the slot smooth and regular clear across. Progressively and alternately the teeth of this broach cut out the 130

central and lateral portions of the slot until the latter is completed throughout its entire length.

The cutting edge 24 of each tooth 20 projects a trifle less than such edge of the tooth 20 immediately behind, of course, and so, also, with the associated teeth 5 and their cutting edges 7.

Although the lands between the channels 8, in which the teeth 20 are located, extend under or beyond the inner edge portions of the chips cut by the teeth 5, said chips readily pass over such lands into said channels, owing to the fact that the lands are convex and considerable portions of said teeth 5 extend over said channels.

The fourth broach, that shown in Figs. 10 and 11, is a widening tool having three rows of teeth 24 and the same number of pilots 9, although it might have more or less than three rows of teeth and pilots, and by omitting the latter the tool might be used for cutting original slots. With the triple rows of teeth three longitudinal chip-clearance channels 8 are required, instead of two as in the other broaches. The exterior faces of the pilots 5 and of the teeth 25 are convex, because this broach is designed to widen grooves or slots which require such faces, but the latter might be flat like the faces of similar members in the broaches previously described, and, contrariwise, the exterior faces of the pilots and teeth of said last-named broaches might be convex.

Each tooth 25 is shaped generally like an arrow head, and arranged on the shank 1 point forward with the cleft behind. The pointed-end portions of the teeth 25 are beveled to form V-shaped cutting edges 37 of the upper or outer edges of such portions. A transverse lug 26 is provided on the inside of each tooth 25, and such lug is receivable in a transverse slot in that part of the shank 1 upon which said tooth is mounted. Screws 27 are employed to secure the teeth 25 in place. Each succeeding tooth 25 from front to rear is set farther from the axial center of the shank, as in the other cases and for the same reason. V-shaped channels 28 for the chips are made in the shank between adjacent ends of the arrow-shaped teeth in each row, so that the chips cut by said teeth pass clear of the latter on both sides into said channels and thence into the channels 8.

In Fig. 13 a piece of stock 13 is shown, through which are a main passage 14 and three slots 29. The fourth broach is designed and adapted to widen the slots 29, in practically the same manner as the first broach is adapted and designed to widen the slot 15 in Fig. 5. The peripheral walls of the slots 29 are concave, and the teeth 25 and associated pilots conform to the shape of said walls, as previously observed. The

middle portions of the teeth 25 or the portions thereof that are directly in line with the pilots do no work, but the outlying portions of said teeth or of their cutting edges 37 cut away the stock radially and widen the slots 29, as indicated by broken lines 30 in Fig. 13.

The fifth and last broach shown, that in Figs. 14 and 15, is an example of a spiral, widening tool which includes another form of tooth, but, nevertheless, embodies my invention. There are two oppositely disposed spiral rows of teeth 31 on the shank 1 in this case, and two pilots 9, and the outer faces of said teeth and pilots are convex, but there might be more or less than that number of rows of teeth and pilots, such row or rows might be straight, and said outer faces thereof might be flat. There is a longitudinal channel 8 on one side of each row of teeth 31, in the shank 1, said shank has two flattened surfaces 32 upon which said teeth are mounted, and there are obliquely-transverse channels 33 in said flattened surfaces between the teeth, each of said channels 33 opening at one end into one of said longitudinal channels. The channels 8 and the flattened surfaces 32 are spiral, and said flattened surfaces have an outward incline from front to rear, longitudinally of the shank, for the purpose of giving to the teeth 31 the different, required amounts of projection, without making said teeth of different thicknesses or setting any of them into the shank, the inner faces of the teeth being beveled slightly to conform to the inclinations of said surfaces.

Each tooth 31 is a rhomboid in shape placed obliquely on one of the flattened surfaces 32, and has a cutting edge 34 on the front as in all cases. On the inside of each tooth 31 is a longitudinally extending rib 35 which is received in a corresponding slot in the shank 1, and two screws 36 are used with this rib, to secure said tooth in place. In front of each tooth 31 is one of the short or branch channels 33, and such channel pitches from one edge of the flattened surface 32 in which it is located, downwardly or inwardly to the connecting channel 8, the deeper portion of the said first-named channel being adjacent to the more rearward portion of the cutting edge 34 of said tooth.

It is now seen that, as the teeth 31 shear off the stock, in the operation of widening a slot, the chips pass down into the branch channels 33, through the latter into the channels 8, and thence away at the rear end of the broach.

In order to distribute properly the strain on this tool, oppositely disposed teeth 31 are placed substantially at right angles to each other, as represented in Fig. 14 wherein is indicated by broken lines 131 a tooth on the

side of the shank opposite to that therein shown.

The fifth broach becomes an initial-slot-cutting tool upon omitting the pilots.

- 5 It is an advantage to employ attachable and detachable teeth, and pilots where used, as I prefer to do and have represented in the drawings, not only because it is frequently less expensive to construct a broach 10 with such attachable and detachable members, but on account of the fact that such members when damaged or broken can be taken out, repaired, and replaced, or replaced with new ones, without being obliged 15 to discard the entire broach. The manner of removing and replacing any of the teeth and pilots will be readily understood from the drawings and hereinbefore given description.
- 20 It is plain that one of the most important and necessary factors in the present invention is the depressed surface, clearance passages or channels provided within or inside of the major diameter and opening at the 25 rear end of the shank, for the chips cut by the front edges of the teeth, in each case. Without the aforesaid channels the tool would be rendered practically useless because of the clogging effect of the chips.
- 30 The terms, outer, transverse, as applied to the cutting edges of the teeth in this case, are intended to apply to the cutting edges of all of the teeth, those in Figs. 10 and 14 as well as those in the preceding views.

What I claim as my invention, and desire 35 to secure by Letters Patent, is—

1. A broach comprising a shank having longitudinal channels formed in the periphery and opening at the rear end of said shank, and a row of teeth on that part of 40 said shank which is between said channels, said teeth having outer transverse cutting edges.
2. A broach comprising a shank, and teeth, having outer transverse-cutting edges 45 on said shank, the latter having depressed surface clearance passages arranged within the major diameter and opening at the rear end of said shank, to receive the chips made by said teeth.
3. A broach comprising a shank, and alternately arranged narrow and wide teeth on said shank.
4. A broach comprising a shank, and alternately arranged narrow and wide teeth 55 on said shank, with an extra, wide tooth at the rear end.
5. A broach comprising a shank, and alternately arranged narrow and wide teeth on said shank, the latter having lateral and 60 longitudinal interior clearance passages for the chips cut by said narrow teeth, and depressed surface clearance passages for the chips cut by said wide teeth.

JOHN OAKLEY.
